CLAIM

The ornamental design for a ram-air intake, as shown and described.

DESCRIPTION

This application is related to U.S. Design application Ser. No. 29/794,450 filed on Jun. 11, 2021 entitled "Ram-Air Intake" and U.S. Design application Ser. No. 29/794,452 filed on Jun. 11, 2021 entitled "Ram-Air Intake", which are assigned to the same Assignee as this application.

FIG. 1 is a perspective view of a ram-air intake showing my new design;

FIG. 2 is a first side view thereof;

FIG. 3 is a second side view thereof;

FIG. 4 is a top view thereof;

FIG. 5 is a bottom view thereof;

FIG. 6 is a back view thereof; and,

FIG. 7 is a front view thereof.

The broken lines illustrate portions of the ram-air intake that do not form a part of the claimed design.
